ELECTRICAL CONTROL SYSTEM

Gustav E. Urdy, Detroit, Mich., assignor to Wel-
tronic Company, Detroit, Mich., a corporation
of Michigan

Application December 15, 1944, Serial No. 568,317

13 Claims. (Cl. 315—201)

1

The present invention relates to electrical control systems and is particularly directed to the provision of improved and simplified means for effecting the starting of mercury arc rectifiers of the so-called mercury pool immersed igniter type.

Principal objects of the present invention are to provide a system of the aforesaid type which is simple in arrangement and which is reliable and efficient in operation; to provide such a system wherein the initiation of a discharge between the main electrodes of a rectifier serves to substantially if not entirely eliminate the flow of current to the igniter electrode of the rectifier; and to generally improve and simplify the arrangement of systems of the aforesaid type.

With the above as well as other and more detailed objects in view, which appear in the following description and in the appended claims, a preferred but illustrative embodiment of the invention is shown in the accompanying drawing in which the sole figure is a diagrammatic view of a control system for a resistance welder, embodying the invention.

It will be appreciated from a complete understanding of the present invention, that in a generic sense, the improvements thereof may be embodied in control systems designed for widely differing applications, and such control systems, and the rectifiers controlled thereby may themselves be of widely differing constructions and arrangements.

In the drawing, a pair of usual mercury arc rectifiers 10 and 12 are connected, in anti-parallel relation, to control the flow of current from an alternating current source L1—L2, to an illustrative load L. Load L is illustrated as being a usual resistance welding circuit, the work-engaging electrodes 14—16 whereof are connected in a local circuit with the secondary winding of a usual welding transformer.

Rectifiers 10—12 are illustrated as being of the conventional mercury pool immersed igniter type, known to the trade as ignitrons. As will be appreciated, these rectifiers, though normally non-conductive, can be rendered conductive, when their anodes a are sufficiently positive with respect to their cathodes c to sustain a discharge, by passing a current of a predetermined magnitude between the igniter i and the cathode c. Such igniting or make alive current serves to establish a cathode spot on the pool type cathode in consequence whereof the main discharge is initiated. When the main discharge is thus initiated, the igniter loses control, and the discharge continues so long as the above described discharge

sustaining potential is maintained between the anode and the cathode.

In accordance with the present invention, rectifiers 10 and 12 are provided with identical firing circuits. More particularly, the igniter i of rectifier 10 is connected to the cathode through a circuit which includes in series a usual unidirectional conductor 18 and the secondary winding 20 of a control transformer CT. The igniter circuit for rectifier 12 includes corresponding elements 22 and 24. The primary winding 26 of control transformer CT is connected across the anodes of rectifiers 10 and 12, in series with a control device 28 which is herein illustrated as being a manually operable pilot switch.

As to operation, it will be appreciated that so long as line conductors L1 and L2 are energized, the line voltage is impressed across the anode-cathode circuit of each rectifier 10 and 12. Normally, being nonconductive, these rectifiers serve as a circuit breaker which prevents flow of current to the load.

In order to initiate a flow of current to the load, switch 28 may be closed, which operation for present purposes, may be assumed to take place at random relative to the periodicity of the source. Assuming that conductor L1 is positive at the time switch 28 is closed, it will be appreciated that such closure initiates a flow of current through winding 26, in a direction which causes the induced voltage in winding 20 to render its associated igniter i positive with respect to the corresponding cathode c. Rectifier 18 is poled to permit a flow of current under these conditions and in consequence thereof an igniting current flows between the igniter i and its cathode c. This flow of current initiates a discharge between the anode and the cathode of rectifier 10. As soon as this main discharge is initiated, the potential difference between line conductor L1 and terminal 30 falls to a comparatively low value, equal only to the arc drop through rectifier 10. Rectifier 10 thus serves to virtually short circuit transformer winding 26, causing the induced secondary voltage thereof to fall to a correspondingly low value.

Under the aforesaid starting conditions, the voltage induced in secondary winding 24 tends to cause current flow in a direction in which rectifier 22 is non-conductive. Substantially no current, whatsoever therefore passes through the igniter circuit of rectifier 12 under conditions when rectifier 10 is to be fired.

At the conclusion of the half cycle of current flow through rectifier 10, the discharge there-through is extinguished. At the instant that this

discharge is extinguished, the voltage across transformer winding 26 again rises to an effective value. At the time conductor L1 is negative with respect to conductor L2, consequently the induced voltage in transformer winding 24 is of the proper polarity to cause a flow of firing current through the igniter circuit of rectifier 12, such current in the firing circuit of rectifier 10 being blocked by rectifier 18. The flow of firing current in the firing circuit of rectifier 12 initiates a discharge therethrough, again virtually short circuiting winding 26 and interrupting further flow of any substantial amount of current in the associated firing circuit.

So long, therefore, as switch 28 remains closed, rectifiers 10 and 12 are alternately rendered conductive. If switch 28 is opened, such action has no immediate effect upon the flow of load current during the half cycle then in progress. Such load current is interrupted when the then active rectifier is extinguished, at the conclusion of such half cycle. In view of the now open condition of switch 28, no flow of load current is initiated through the companion rectifier at the beginning of the following half cycle.

It will be appreciated that in practice transformer CT is arranged so that the secondary outputs are of sufficient magnitude to insure prompt firing of the associated main rectifiers, under the aforesaid conditions. At the same time transformer CT is so proportioned that the secondary outputs, when either main rectifier is conductive, are so low as to have no adverse effect on the igniters i.

It will further be appreciated that switch 28 may be subjected either to manual or automatic control and that it may be regarded as representing, for example, an electrically or mechanically operated element which "closes" and "opens" in synchronizing relation to the source L1—L2.

Although only a single specific embodiment of the invention has been described in detail, it will be appreciated that various modifications in the form, number, and arrangement of the parts may be made without departing from the spirit and scope of the invention.

What is claimed is:

1. In a control system for an electric valve of the immersed igniter mercury pool type, having principal electrodes, and disposed to abruptly change from a non-conductive to a conductive condition in response to the application of a critical potential to said igniter for controlling the flow of current between a source of supply and a load, the combination of an electrical translating device adapted to supply said critical potential, means including unidirectionally conductive means for coupling said translating device between said igniter and one of said principal electrodes, control means for controlling the energization of said translating device and having a first control position in which said translating device is enabled to supply said critical potential, and means responsive to a conductive condition of said valve for reducing the energization of said translating device to a potential not in excess of the potential between said principal electrodes.

2. The combination of claim 1 wherein said translating device is a transformer, having its secondary winding coupled between said igniter and said one principal electrode, and having its primary winding connected in parallel with the principal electrodes of the valve whereby the potential impressed on said primary winding is

the same as the potential across the principal electrodes.

3. The combination of claim 1 wherein said translating device is a transformer, having its secondary winding coupled between said igniter and said one principal electrode, and having its primary winding connected in parallel with the principal electrodes of the valve whereby the potential impressed on said primary winding is the same as the potential across the principal electrodes, and said control means is selectively operable for controlling said connection for said primary winding.

4. In a control system for controlling the flow of current from an alternating current source to a load, a pair of reversely connected discontinuous control-type electric valves each having principal electrodes and a control electrode, a transformer having a primary winding connected between one of said principal electrodes of each of said valves and having a pair of secondary windings, means adapted to connect the principal electrodes of each of said valves in series circuit between the load and the source, and means connecting each secondary winding between the control electrode and the other of said principal electrodes of the corresponding valve.

5. The combination of claim 4 wherein each said secondary connection includes unidirectionally conductive means.

6. The combination of claim 4 including selectively operable control means for controlling the energization of said primary winding.

7. In an electrical network for controlling the flow of alternating current from a source to a load, a pair of mercury pool-type electric valves, each said valve having an anode and a cathode and an igniter, means adapted to be connected to the source and electrically interconnecting said anode of one of said valves with said cathode of the other of said valves, means adapted to be connected to the load and electrically interconnecting said anode of said one valve, a transformer having a primary winding and a pair of secondary windings, means connecting said primary winding directly across said anodes, means connecting one of said secondary windings between said igniter and said cathode of said one valve, and means connecting the other of said secondary windings between said igniter and said cathode of said other valve.

8. In an electrical network for controlling the flow of alternating current from a source to a load, a pair of mercury pool-type electric valves, each said valve having an anode and a cathode and an igniter, means adapted to be connected to the source and electrically interconnecting said anode of one of said valves with said cathode of the other of said valves, means adapted to be connected to the load and electrically interconnecting said anode of said other valve with said cathode of said one valve, a transformer having a primary winding and a pair of secondary windings, means connecting said primary winding directly across said anodes, means connecting one of said secondary windings between said igniter and said cathode of said one valve, means connecting the other of said secondary windings between said igniter and said cathode of said other valve, and switch means for controlling the energization of said primary winding.

9. In an electrical network for controlling the flow of alternating current from a source to a load, a pair of mercury pool-type electric valves,

each said valve having an anode and a cathode and an igniter, means adapted to be connected to the source and electrically interconnecting said anode of one of said valves with said cathode of the other of said valves, means adapted to be connected to the load and electrically interconnecting said anode of said other valve with said cathode of said one valve, a transformer having a primary winding and a pair of secondary windings, means connecting said primary winding directly across said anodes, means connecting one of said secondary windings between said igniter and said cathode of said one valve, means connecting the other of said secondary windings between said igniter and said cathode of said other valve, and unidirectional current conducting means interposed in each of said secondary connecting means whereby current can flow solely from said igniters to said cathodes, each of said secondary windings being so phased relative to its respective one of said valves to provide current flow when said anode of said respective valve is positive relative to its cathode.

10. In an electrical network for controlling the flow of alternating current from a source to a load, a pair of mercury pool-type electric valves, each said valve having an anode and a cathode and an igniter, means adapted to be connected to the source and electrically interconnecting said anode of one of said valves with said cathode of the other of said valves, means adapted to be connected to the load and electrically interconnecting said anode of said other valve with said cathode of said one valve, a transformer having a primary winding and a pair of secondary windings, means connecting said primary winding directly across said anodes, means connecting one of said secondary windings between said igniter and said cathode of said one valve, means connecting the other of said secondary windings between said igniter and said cathode of said other valve, unidirectional current conducting means interposed in each of said secondary connecting means whereby current can flow solely from said igniters to said cathodes, each of said secondary windings being so phased relative to its respective one of said valves to provide current flow when said anode of said respective valve is positive relative to its cathode, and switch means for controlling the energization of said transformer.

11. In a control system for an electric valve of the immersed igniter mercury pool type having principal electrodes and disposed to abruptly change from a nonconductive to a conductive condition in response to the application of a critical potential to said igniter for controlling the flow of a current between a source of supply and a load, the combination of an electrical

- 5 transformer having a primary and a secondary winding and adapted to supply said critical potential, circuit means including unidirectional conductive means for coupling said secondary winding between said igniter and one of said principal electrodes, control means for controlling the energization of said transformer and having a first control position in which said transformer is enabled to supply said critical potential, and means responsive to a conductive condition of said valve for reducing the output potential of said secondary winding to a potential not in excess of the potential between said principal electrodes.
- 10 15 12. The combination of claim 11 in which said unidirectional means permits flow of substantial current solely in a direction toward said igniter from said secondary winding.
13. In a control system for controlling the flow of current from an alternating source to a load, a pair of reversedly connected electric valves of the immersed igniter mercury pool type each having principal electrodes and disposed to abruptly change from a nonconductive to a conductive condition in response to the application of a critical potential to said igniter for controlling the flow of current therethrough, a transformer having a primary winding with its terminals connected between corresponding ones of said principal electrodes of each of said valves and having a pair of secondary windings, circuit means adapted to connect the principal electrodes of each of said valves in series circuit between the load and the source, and circuit means including a unidirectional current flow device for connecting respective ones of said secondary windings between the respective said igniters and the other of said principal electrodes of corresponding valves, said flow devices permitting substantial current to flow only in a direction from said secondary windings to said igniters.
